PAPER-REELING MACHINE

Application filed September 23, 1926, Serial No. 137,345, and in Japan October 13, 1925.

This invention relates to improvements in a paper reeling machine which continuously reels up paper coming from a paper making machine at a constant tension.

The object of this invention is to provide an automatic electric speed-governing means by which the reel increases or decreases its speed automatically in accordance with decrease or increase of tension of the paper to be reeled, so that the tension is always constant.

A further object of this invention is to provide a speed regulating means of a motor by which the reeling speed of paper is easily regulated at will.

A further object of this invention is to make unnecessary the use of the mechanical driving means which is generally adopted for paper reeling machines but which is noisy and cannot sensitively govern the speed of a reel.

A further object of this invention is to provide a reel with suction means therein, so that a free end of paper can be easily moved to adhere to the surface of the reel which gets to its working position.

In a known reeling machine, a plurality of reels, for example, six in number, are mounted on a rotary frame in radial direction at the same distance from the axis of the frame, and the frame rotates intermittently when the reel in the working position has reeled up paper thereon, so as to bring the next reel to the working position. Such a rotary frame with reels thereon is used also in this invention.

In the present invention an induction motor is directly coupled to each reel and the reels as well as the motors are kept on the rotary frame. All of the motors, for example, six, are supplied with electric current from an extraneous source, and the rotor armature of each motor when it is in working position is electrically connected with the stator coil of another inductor motor through a series of rings described later on. By this means the motors coupled to the reels, which are called reel-motors hereinafter, cooperate with the second inductor motor one by one, the latter motor being called as an idle-motor

in this specification. The idle-motor is loaded with such a load that the amount of the load proportionally varies with change of its speed. The principle of this invention is as follows: In case the paper which is being reeled slacks or the tension of the paper decreases, the load on the corresponding reel-motor decreases, so that the reel-motor increases its speed a little. The increase of speed, however, is not so great immediately as to wind up the slackened paper to the point at which its normal tension is at once resumed. But as the speed of the reel-motor thus increases, that is to say, as the magnetic slip of its rotor decreases, the voltage induced in the rotor instantaneously drops, so that the rotor of the idle-motor connected to the reel-motor decreases its speed. When the rotor-speed of the idle-motor decreases, the load on the rotor decreases, and the stator-current also decreases. Thus the rotor-current of the reel-motor decreases, so that the torque of the reel motor is decreased, a corresponding decrease in voltage in the rotor is accentuated due to the kind of load imposed upon the idle motor, and the speed of the reeled motor is increased. This increase of speed quickly winds up the slackened paper till the paper-tension increases up to the normal value.

When the paper tension is too large, the two motors cooperate reversely to the above and always govern the speed of the reel to keep the proper tension of the paper.

The details of my invention will be further described, reference being had to the accompanying drawings.

Fig. 1 is a plan view of a paper reeling machine according to my invention.

Fig. 2 is a sectional side elevation of Fig. 1.

Fig. 3 is a diagrammatic view of the electrical connection between the reel-motors and idle motors.

Fig. 4 is a front elevation of a vacuum distributing means for the reels, and

Fig. 5 is a sectional side elevation of the same.

In the drawing, 1 is a reel, six of which, in this instance, are mounted in bearings provided on a rotary frame 4 mounted on a shaft 3. Each reel is directly coupled with

an induction motor 6 through a coupling 5 and is driven by the motor. The motors are held on the frame 4 on which the reels are distributed in radial direction and are positioned at constant distance from the axis as clearly shown in Fig. 2.

Each reel is made of a hollow cylinder with a number of small perforations over the surface, and the end opposite to the motor is connected through a pipe to a source of vacuum. In Fig. 5, 15 is a disc firmly held on the frame of the machine, which is provided with a vacuum pipe 16. 17 is a disc firmly held on the shaft 3, and six pipes 18 run from this disc to the ends of the six reels. The surfaces of the discs 15 and 16 are closely kept in contact with each other, and only the pipe 18 of the reel which is in the working position registers with the vacuum pipe 16, so that only the reel in the working position is connected to the source of vacuum.

The shaft 3 is driven by a motor 12 through worm and worm gear 11 and spur gears 8. The motor 12 runs intermittently. Intermittent operation of the motor 12 is regulated by any known means which closes a switch in the circuit of the motor when the reel in working position has reeled up paper till it attains to a predetermined diameter, and then opens the switch when the rotary frame has turned to such a position that the next reel comes to the working position.

14 is a series of rings firmly fixed on the machine frame concentrically to the shaft 3 and controlling the electrical connections between the outer electric source and the reel-motors 6, and those between the rotors of reel-motors and stators of idle-motors 13^a and 13^b. The rings comprise three groups *a*, *b* and *c*, and each group consists of three rings. Each ring is insulated from the other rings and from the frame of machine. Five-sixths of the outer periphery of the rings is covered by insulation and the metallic surface exposed in the remaining one-sixth part, and all of the rings are arranged in such a manner that the metallic part extends in the same direction.

Each ring of the first group *a* is connected to each line *i* of a three-phase alternating current source, and six sets of brushes distributed on the rings are connected to each of the six reel-motors 6 as shown in Fig. 3. Each set of the brushes consists of three brushes, respectively contacting with each of the three rings of the first group *a*, and each brush is connected to each phase of the stator of the corresponding three phase induction motor 6.

The second and third groups of rings have three sets of brushes respectively (each set of brushes consisting of three brushes and each brush being electrically connected to each phase of the rotor of the motor 6 through "slip rings) and the three sets of brushes on

the second group are connected to three alternate reel-motors, while the three sets of brushes on the third group are connected to the three remaining reel-motors, and the brushes on the second group and those on the third group are displaced on the periphery in the same angular distance.

Fig. 3 shows the electrical connection above described. It shows, however, only the connection of one phase of each motor, therefore, one ring, one line or one brush should be understood as three rings, three lines or three brushes respectively. The first, second and third groups of rings, *a*, *b* and *c*, are of same diameter, but they are shown in Fig. 3 as concentric rings. *d*₁, *d*₂, *d*₃, *d*₄, *d*₅ and *d*₆ are lead lines connecting the stator of each reel-motor to the first group of rings *a*, *e*₁, *e*₂ and *e*₃ connect the rotor of the motors *A*, *A*₁ and *A*₂ with the third group ring *c* and *f*₁, *f*₂ and *f*₃ connect the rotor of the motors *B*, *B*₁ and *B*₂ with the second group ring *b*. The line *g* is a lead wire to the stator of the idle-motor 13^a from the third group of rings while the line *h* is that of idle-motor 13^b from the second group of rings. The lead wire *i* from outer source of three phase alternating current is connected to the first group of rings. The lines *i*, *h* and *g* are always in electrical connection with the rings *a*, *b* and *c*, respectively, while other lines get in electric contact with the rings only one sixth part of the periphery.

Each idle motor drives a blower 9 and is provided with a friction brake 10.

Suppose a reel *A* is in the working position *W*, then the motor *A* (the motor for the reel *A* is denoted by *A*) receives current from the line *i*, and its rotor is electrically connected to the stator of the idle motor 13^a through the lines *e*₁ and *g*.

When the reel *A* has reeled up paper sufficient in length and gets to a predetermined diameter, the frame 4 with all the reels and reel-motors turns 60 degrees as above described. When the frame turns about 30 degrees or to the middle point (Fig. 3 shows the positions of the members at this point), the brushes of lines *d*₁ and *e*₁ come out of electric contact with the rings *a* and *c* or the lines *i* and *g*, while the brushes of lines *d*₆ and *f*₃ get in electric contact with the rings *a* and *b* or the lines *i* and *h*, so that the reel *A* and the idle-motor 13^a stop and reel *B* and the idle-motor 13^b begin their rotation.

When the working reel is full of paper, the paper which is being reeled on the roll is cut by means of a known mechanism, which is actuated by an electric magnet excited at the proper moment, and the free end of paper is easily attached to the surface of the reel *B* by the suction of its interior vacuum. In this way, the reel motors come in operation one after another, and the idle motors rotate alternatively. The reel-motors *A*, *A*₁ and *A*₂

cooperate with the idle motor 13^a and the reel motors B, B₁ and B₂ cooperate with the idle motor 13^b, and the speed of the reel-motors is automatically governed by the idle-motors as before described.

5 If the speed of the reel is required to be changed in accordance to the quality of paper to be reeled, the load on the idle motor should be changed. If the pressure of the friction 10 brake 10 or the delivery area of the blower 9 on the idle-motors is changed, the speed of reel-motors can be easily changed.

The vacuum pipe 18 is connected to a vacuum tank 19, which is connected to a vacuum 15 pump 20. Since vacuum is required only when a new reel begins to rotate, the vacuum pump is not required to be working continuously, therefore, in the example shown in the drawing, it is driven by the motor 12 which 20 operates intermittently.

Of course the brushes should be always kept in definite positions relative to the reel 25 motors and rotate intermittently together with the reel-motors along the periphery of the rings.

What I claim is:—

In a paper reeling machine of the type comprising a plurality of reels mounted in a rotary frame, each brought into working position by intermittent rotation of said frame, a plurality of induction motors one for each reel, to the rotors of which the reels are coupled, and two auxiliary motors, means connecting the rotors of the alternate reel motors 30 to the stator of one of said auxiliary motors while the rotors of the remaining reel motors are connected to the stator of the other auxiliary motor, the connecting means consisting of three groups of three rings and three 35 groups of brushes contacting thereon, each of the rings being covered for five-sixths of its peripheral surface with insulating material, the three rings of the first group being electrically connected with each phase of three 40 groups of alternating current from an external source and with the rotors of six reel motors, and the three rings of the second and third groups being electrically connected with the 45 stators of the two auxiliary motors and with the rotor of six reel motors, and the time 50 of electrical connection of the external source with the reel motors and that of the auxiliary motors being controlled by the proper position of the brushes on the rings.

55 In testimony whereof I hereunto affix my signature.

WASABURO OKUURA.
